UNITED STATES PATENT OFFICE.

HERMAN L. GREVE, OF NEW YORK, N. Y.

MAILING WRAPPER.

Application filed July 9, 1919. Serial No. 309,742.

To all whom it may concern:

Be it known that I, HERMAN L. GREVE,
a citizen of the United States, and resident
of the city of New York, in the county of
5 Kings and State of New York, have invent-
ed certain new and useful Improvements in
Mailing Wrappers, of which the following
is a specification.

My invention relates to mailing wrappers and particularly to mailing wrappers for books.

The object of the present invention is to provide an adjustable mailing wrapper that can be adjusted within its capacity to conform to the length of the book to be mailed.

A further object is to provide a wrapper the edges of which are turned to form pleats which overlie and abut the edges of the book enclosed and thus better protect them and also prevent the wrapper from shifting its position relative to the cover of the book.

position relative to the cover of the book. Referring to the drawings which form a part of this specification,

Fig. 2 is an end view thereof:

Fig. 2 is an end view thereof;

30 Fig. 4 is an end view thereof.

Fig. 5 is a view of the inner

complete wrapper and
Fig. 6 is an end view thereof.

Fig. 7 is a perspective view of

35 per as it appears when inclosing a book ready for mailing.

A and B indicate the two body portions of the wrapper which is made of strong flexible paper or other suitable material and C indicates the outer edge portions, which are folded over and cemented to form a pleat at each outer edge on the inner side thereof and which rests on the edge of the book as illustrated at D in Figure 7.

45 The portion A is formed with a side portion E, the ends E'-E' of which are passed through the slots F-F formed in the portion B and cemented together as shown at G in Figure 5, forming a slide-band which
50 is free to move the length of the guide portion H, and which holds the two body portions together.

The book to be wrapped is laid in the wrapper so that its top and bottom ends are located opposite the edges C and the portions A and B then pressed toward each

other until the shoulders C' rest in contact with the ends of the book cover, then the ends of the wrapper are folded to inclose the book and the whole package secured by means of the cord I and button J as illustrated.

Having thus described my invention I claim as new and desire to secure by Letters Patent:—

1. A mailing wrapper for a book comprising a body portion made of thin flexible material, consisting of two parts of equal length, which are relatively detachable and the inner edges of which are held together in overlapping and adjustable relation to each other. 70

2. A mailing wrapper for a book comprising a body portion made of thin flexible material and having two parts of equal length held together and relatively adjustable and adapted to be folded about a book, said portions being relatively detachable. 75

3. A mailing wrapper for a book made of thin flexible material consisting of two longitudinally extending portions of equal length held together and laterally adjustable relative to each other, said portions being relatively detachable. 80

4. A mailing wrapper for a book made of thin flexible material consisting of two longitudinally extending portions of equal length held together and laterally adjustable relative to each other and each portion having its outer edge turned to form a shoulder, said portions being relatively detachable. 85 90

5. A mailing wrapper for a book made of thin flexible material consisting of two longitudinally extending portions of equal length held together and laterally adjustable relative to each other and each portion having its outer edge turned to form a shoulder adapted to extend around the end of the enclosed package, and means connected to said body portion for securing it in position on a book, said portions being relatively detachable. 95 100

6. A mailing wrapper for a book comprising a body portion made of thin flexible material and having two parts of equal length and relatively adjustable and adapted to be folded about a book and cover the same, and means connected to said body portion for securing it in position on a book, said portions being relatively detachable. 105 110

7. A mailing wrapper for a book made of

thin flexible material consisting of two longitudinally extending portions of equal length and comprising a slide band and guide for holding them together in adjustable relation, said portions being relatively detachable.

8. A mailing wrapper for a book made of thin flexible material consisting of two longitudinally extending portions of equal length and comprising a slide band and guide for holding them together in adjustable relation, and the edges of which are folded over to increase their stiffness, said portions being relatively detachable.
- 10 9. A mailing wrapper for a book made of

thin flexible material consisting of two longitudinally extending portions of equal length comprising a slide band and guide for holding them together in adjustable relation, and the edges of which are folded over to increase their stiffness, said portions being relatively detachable. 20

Signed at New York city, in the county of Kings and State of New York, this 8th day of July, A. D., 1919.

HERMAN L. GREVE.
